Charles Howell
Gordon Patent

The Schedule referred to in these Gordon Patent and making part of the same containing a description in the name of the said Charles Howell himself of his improvement in the Rotary Steam Engine operating upon the principle of reaction.

To all whom it may concern. Be it known that I, Charles Howell of Zanesville in the state of Ohio have invented certain improvements in the Rotary Steam Engine operating upon the principle of reaction and that the following is a full and exact description of my said improvements.

Fig. 1 in the accompanying drawing represents the general plan and arrangement of my improved engine, the various parts however being susceptible of numerous modifications whilst the principle of its action remains unchanged. A represents a revolving wheel, within which is contained various parts as hereinafter described. B. is a hollow shaft, to which the wheel is attached, sufficiently supported at the ends and receiving steam from a boiler or through a connecting pipe at D. and then kept steam tight by means of a stuffing box or otherwise. C. C. are small steam pipes leading in opposite directions from the hollow shaft towards the periphery of the wheel and well protected by nonconducting coverings. D. D. are the contracted commencement of the pipes D. D. which pipes D. D. lead from the pipes C. C. in a cubic course proceeding to the periphery of the wheel, and enlarge to any desired dimensions. E. E. are continuations of the same steam pipes in connexion with the water pipes F. G. herein after described. H. H. are continuations of the same pipes in opposite courses suitably contracted terminating beyond the periphery of the wheel, at G. G. with jets at right angles therewith and opposite to its direction. I. is a circular opening on one side of the wheel into which water is conveyed by means of a pipe or otherwise from a suction pump. J. are water pipes leading in opposite directions from the opening I. to C. C. where the said water pipes open a small bore respectively to H. H. constituting parts of the steam pipes from C. C. to H. H. as here

before mentioned. The cold water pipes continue from thence to their terminations at H. H., beyond the periphery of the wheel, terminating with spouts the same as those of the steam pipes at G. G. The water pipes from C. C. to N. N. may surround the steam pipes encasing the same or pass within them or be continued in any manner which will present a sufficient surface for the condensation of the steam. The water pipes are connected by a pipe M. for the purpose of equalizing the quantity of water in the pipes H. H. the revolving wheel may be enclosed in a casing of wood or metal of a circular or other form within which the water and condensed steam may escape and from thence be conveyed as convenience may direct. The wheel may be otherwise used as a condenser by means of water applied to its outer surface, dispensing with the water pipes as described and terminating the steam pipes at C. C. but still using a serpentine conveyance for the condensed steam as in Fig 1. The whole may then be enclosed within a casing as before. Instead of allowing the steam to escape from a fixed boiler through a steam tube at the top I sometimes allow the whole boiler to revolve with the wheel. In this case the steam tube extends out from the centre of one head of the boiler. Their axes coinciding with each other. This pipe then constitutes the shaft to which the wheel A. is affixed as in Fig 1. The other end of the boiler is supported upon a hollow gudgeon through which water is to be supplied. The whole quantity of water contained therein at any one time may be small the over heating the boiler being prevented by the constant diffusion of the water over its inner surface.

Mode of Operation. The steam from a boiler entering a revolving shaft at N. passes through the pipes C. C. and the contracted points L. L. to the enlarged pipes D. D. The enlargement of these pipes reduces the velocity of the steam and proportionately increases the surface against which reaction takes place. The extremely rapid motion which would be necessary to ensure the full application of the steam if allowed to escape immediately from the contracted points is thereby avoided. The steam arriving at L. L. comes in contact with the exposed surface of the cold water pipes and is condensed creating a vacuum and the condensed steam is thrown out by its centrifugal force at the spouts G. G. The condensed steam

down within the centrifugal pipe will by means of the centrifugal force maintain the vacuum against the outward pressure of the atmosphere thereby increasing the effective power of the steam fifteen times to the inch. Water is introduced at the opening I, in sufficient quantity for the purpose of the engine and is thrown by its centrifugal force through the proper tubes and by its reaction at the spout H. It compensates for the power which is expended in giving it momentum. Air may be used separately or in connection with water for condensing the steam with suitable alterations of the opening I, and the tubes connected therewith. What I claim as my invention in the hereinbefore described machine is the principle of increasing the surface of reaction and diminishing the motion without diminishing the power of the steam which is effected by the enlargement of the steam pipes (as at D. D.) and the vacuum created by the condensation of the steam giving a leeway to the wheel accompanied with a corresponding increase of power. I also claim as my invention the introduction of water and air either separately or in connection for the purpose of creating the vacuum, and the manner of introducing and disposing of the same, together with the manner of disposing of the steam so as to effect in maintaining the vacuum. And I also claim as my invention the application of the principles to attain the object herein set forth, whether the same be effected in the precise manner described or otherwise.
